(57) **CLAIM**

The ornamental design for a ladder receiving bucket hanging
bracket assembly, as shown and described.

DESCRIPTION

FIG. 1 is a top perspective view of the ladder receiving
bucket hanging bracket assembly showing my new design;

FIG. 2 is a front elevation view;

FIG. 3 is a top plan view;

FIG. 4 is a bottom plan view;

FIG. 5 is a left side elevation view;

FIG. 6 is a right side elevation view; and,

FIG. 7 is an overall perspective view of the invention being
mounted on a bucket prior to being received into a ladder
rung.

The broken lines showing a ladder rung and a bucket are for
illustrative purposes only and do not form a part of the
claimed design.
